ELLIS L. WILSON, OF SAN ANSELMO, CALIFORNIA.

DOOR HINGE.

Application filed August 3, 1925. Serial No. 47,719.

This invention relates to door hinges and the like, and especially to an adjustable type of hinge.

The object of the present invention is to generally improve and simplify the construction and operation of adjustable door hinges and particularly to provide a hinge whereby a door may be pulled back into place if it has warped or is slightly out of line for any reason, and to provide a hinge which eliminates the necessity of removing the door or the hinges when fitting the door.

The invention consists in forming yielding members on the leaves of the hinge whereby the hinge may be adjusted to or away from the jam or frame.

One form which the hinge may assume is exemplified in the accompanying drawing, in which—

20 Fig. 1 is a sectional view of the door jam showing the application of the hinge.

Fig. 2 is a perspective view of the hinge.

Fig. 3 is an edge view of a hinge.

Referring to the drawing in detail, A 25 indicates the leaf sections of an ordinary hinge, 2 the hinge or bearing sections formed thereon, 3 the pipe or pin or pintle, and 4 the holes which are drilled or otherwise formed in the leaves to permit ordinary wood screws 30 to be passed therethrough. The leaf sections are in this instance cut along the lines indicated at 5, and a series of yielding tongues 6 are thereby formed. These tongues are bent slightly as indicated in 35 Figs. 1, 2, and 3, and they form yielding supports for the leaf sections which permit adjustment of the leaves to and away from the door or the jam as the case may be.

In actual practice, the leaves are applied 40 to the door jam C in the usual manner by means of wood screws 7. The screws are pulled up until the tongues 6 engage the surface of the jam and the door is then hung and the pintles 3 applied. If it is 45 found that the door springs from the jam or frame at any particular point, it is only necessary to tighten the screws 7 of one leaf or another, thereby pulling the door or straightening the same to such an extent as 50 to provide the proper clearance.

Again, it may be found that the weight of the door causes sagging or slacking at the upper corner and possibly rubbing of the

same on the threshold. If this is the case, it is only necessary to tighten the screws in 55 the upper leaf sections, thus pulling the upper corner of the door inwardly and immediately relieving the friction at the point where it was previously felt. In other words, the tongues 6 may either become impressed in the wood or may slightly straighten out when pressure is applied to the screws 60 7. Either action causes the leaf to move with respect to the door jam, and it is in this manner that adjustment and alignment 65 is obtained. This is particularly important as it eliminates the necessity of planing off to obtain the proper fit. The cutting of the leaves along the lines indicated at 5 is of 70 further importance as it disposes the hinge or bearing sections 2 at the ends of arms such as shown at 8. These arms may be bent inwardly or outwardly as indicated by dotted lines at 9 and thereby provide a further adjustment whereby a door, window, 75 gate, or the like may be readily adjusted. In other words, adjustment can be obtained by forcing the tongues 6 into the wood or bending the same; or adjustment may be obtained by slightly springing the arms 8 80 carrying the hinge members 2.

While certain features of the present invention are more or less specifically illustrated, I wish it understood that various changes in form and proportion may be 85 resorted to within the scope of the appended claims. I similarly wish it understood that the materials and finish of the several parts employed may be such as the experience and judgment of the manufacturer may dictate 90 or various uses may demand.

Having thus described my invention, what I claim and desire to secure by Letters Patent, is—

1. In a hinge of the character described, 95 a rectangular shaped leaf section, pintle bearing members formed along one longitudinal edge of the leaf section, and bendable tongues formed in the same edge of the leaf and intermediate the pintle bearing 100 members.

2. In a hinge of the character described, a leaf section, said section consisting of a substantially rectangular shaped plate, said plate being cut transversely at a plurality 105 of points along one longitudinal edge to

form a plurality of parallel bendable tongues and each alternate tongue being bent to form a pintle bearing.

3. In a hinge of the character described, a leaf section, said section consisting of a substantially rectangular shaped plate, said plate being cut transversely at a plurality

of points along one longitudinal edge to form a plurality of parallel bendable tongues and each alternate tongue being bent to 10 form a pintle bearing, the tongues carrying the pintle bearings being perforated to receive adjusting screws.
